US00D770858S

(12) **United States Design Patent** (10) **Patent No.:** **US D770,858 S**
Savarese (45) **Date of Patent:** **** Nov. 8, 2016**

(54) **CHAMPAGNE AND WINE BOTTLE CHILLER**

(71) Applicant: **Pasquale Savarese**, Smithtown, NY (US)

(72) Inventor: **Pasquale Savarese**, Smithtown, NY (US)

(**) Term: **14 Years**

(21) Appl. No.: **29/517,006**

(22) Filed: **Feb. 9, 2015**

(51) LOC (10) Cl. **07-01**

(52) U.S. Cl.

USPC **D7/603**

(58) **Field of Classification Search**

USPC D7/354, 523, 603, 605; D3/313
 CPC F25D 3/08; B65D 25/30; B65D 7/24;
